MEASURING SPOON

Granville H. Shirley, Cleveland, Ohio, assignor to
The Van Dorn Iron Works Company, Cleve-
land, Ohio, a corporation of Ohio

Application August 13, 1948, Serial No. 148,099

Term of patent 14 years

(Cl. D44—29)

To all whom it may concern:

Be it known that I, Granville H. Shirley, a citizen of the United States, residing at Cleveland, in the county of Cuyahoga and State of Ohio, have invented a new, original, and ornamental Design for a Measuring Spoon, of which the following is a specification, reference being had to the accompanying drawing, forming a part thereof, wherein:

Fig. 1 is a top plan view of my new design for a measuring spoon;

Fig. 2 is a bottom plan view of the spoon shown in Fig. 1; and

Fig. 3 is a side elevational view of the spoon shown in Fig. 1.

I claim:

The ornamental design for a measuring spoon, substantially as shown.

G. H. SHIRLEY.
